UNITED STATES PATENT OFFICE

2,032,671

CODE CALL APPARATUS

Boyd H. Smith, Shelby, Ohio, assignor to The
Autocall Company, Shelby, Ohio, a corporation
of Ohio

Application May 20, 1931, Serial No. 538,669

2 Claims. (Cl. 172—239)

The present invention, relating as nominally indicated to a code call apparatus, pertains more particularly to an improved mechanism for the transmission of code signals from a central station to a plurality of distant and distributed stations. The instant improvements herein provided for are contemplated to be more precisely applied to the apparatus embodying the principle of invention which forms the subject matter of 5 my prior U. S. Letters Patent No. 1,823,221 granted Sept. 15, 1931.

The code signal impulses transmitted by my apparatus may be made audible or visible, that is, they may be ultimately communicated by means 15 of ringing bells or flashing lights, etc. The fundamental features of novelty in the present invention reside in what may most conveniently be termed a supplemental call system and a variable limited call device. In larger establishments 20 such as factories, stores and offices, where it is desired to summon individuals to a particular place, it is found convenient to provide a system of call signals, each signal having a distinctive code applicable to a certain individual. In order 25 to transmit additional information to such call signals, such as urgency of call, departmental call, etc., my present invention provides for a means for supplementing the regular code signal with a variety of distinctive general calls. It is a further object of my invention to provide means 30 whereby such supplemental calls may be transmitted together with the regular call, or omitted entirely at the will of the central operator.

Furthermore, the regular calls and supplemental calls may be transmitted for an indefinite continuous period, or for a limited number of repetitions at the will of the operator. Such option 35 may be exercised by simple manipulation of the operating and signal-selecting key. It is also possible to transmit the supplemental signals either prior or subsequent to the regular signals. When making the last-named change, in order to maintain a uniform interval between the cessation 40 of the supplemental signals and the inception of the regular code, it is necessary to reverse the coding order of the regular signals. This latter step shall be more definitely described later on in the following description.

Another object of my invention is to provide a means to predeterminately vary the number of limited calls which the apparatus will transmit upon an initial energization by the operating key. Such factors as frequency of calls, availability of 45 the persons summoned, size of the establishment,

etc., are determinative of the desirability and number of repetitions of the limited calls.

Further advantageous features which commend the novelty of my invention shall become apparent as the description proceeds. To the accomplishment of the foregoing and related ends, 5 said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used. 10

In said annexed drawings:

Fig. 1 is a perspective view of the central station apparatus with the cover in position; Fig. 2 is an end elevation of the apparatus of Fig. 1 with the side wall of the cover removed; Fig. 3 is a perspective view of the signal selecting and operating key; Fig. 4 is a perspective view of the revolving switch arm; Fig. 5 is a plan view of the interior of the apparatus embodying the principle of my invention, the cover being removed; Fig. 6 is a section taken substantially upon the line 6—6 of Fig. 5; Fig. 7 is a sectional view taken substantially upon the line 7—7 of Fig. 5; Fig. 8 is a sectional elevation of the supplemental signal switch; Fig. 9 is a section taken substantially on 20 the line 9—9 of Fig. 8; Fig. 10 is a perspective view of the supplemental switch contact disc; Fig. 11 is an elevational view of the supplemental switch rear insulating block; Fig. 12 is a fragmentary sectional view taken substantially on the line 30 12—12 of Fig. 2; Fig. 13 is a sectional view of the motor switch and motor switch operating gear; and Fig. 14 is a wiring diagram illustrative of the various electrical circuits embodied in my apparatus. 35

Referring more particularly to Fig. 1, the exterior construction of my apparatus consists essentially of the base plate 1 having mounted thereon the metallic cover 2 which has the side portion 3 and front portion 4. Positioned in the lower part of the front of the cover 4 is the operating switchboard 5 having the selective circuit sockets 6, the supplemental call switch 7 and the pilot lamp panel 8. A plurality of fastening screws 9 are positioned around the base of the 40 cover 2 in order to removably secure it to the base plate 1.

In Fig. 2 the interior assembly of the mechanism is generally indicated. Immediately behind the switchboard 5 are positioned the selective 45

switch bars indicated generally at 10, the pilot lamp 11, and the supporting brackets 12.

The particular construction and mode of operation of the selective switch bars 10 are not intended to be claimed within the scope of the present invention inasmuch as they are covered by my prior U. S. Letters Patent No. 1,823,221 granted Sept. 15, 1931, and the patent to George Thompson, No. 1,230,946, issued January 26, 1917.

10 More or less centrally positioned upon the base plate 1 is the signal transmitting mechanism. The latter mechanism is resiliently mounted upon the volute springs 14 and 15 in order to minimize vibration and expedite smoothness of operation

15 of the moving parts.

An operating key as shown in Fig. 3 is provided for the purpose of selecting predetermined circuit connections by means of inserting it into the sockets 6. This key 16 consists essentially of the flattened handle portion 17 composed of insulation having positioned therein the cylindrical extension 18 composed of conducting material. On the outer end of the extension 18 is the flattened portion 19 which is adapted to make and break contact with the motor energizing bars positioned in the switchboard panel 5 upon rotation of the key 16.

Referring back to Figs. 2 and 5, the code signal transmitting mechanism includes a sector plate 13 of insulating material having positioned thereon the laterally extending contact pins 20 to 26 inclusive, which are circumferentially disposed and spaced from each other at equal arcuate distances. In the same circumferential line are positioned the supplemental call contact pins 27 to 30 which are also spaced from each other at equal arcuate distances, but such arcuate spacings are different from those of the contact pins 20 to 26 inclusive. Centrally mounted of the 40 above enumerated contact pins is the revolving switch arm 31 having the retaining spring 32 secured in the lateral groove 33 of the metallic block 34 by means of the fastening screw 35. The revolving switch arm 31 has a transverse groove 37 which is adapted to carry the contacting brush 38.

As illustrated by Fig. 5, the general interior layout of the apparatus consists of the driving motor 40, the terminal block 41, the dismissal solenoid 42, the insulated exterior cable collar 43, the metallic gear train journal plates 44 and 45, the dismissal clutch 47, and the motor governor 48.

The driving shaft 50 of the motor 40 (see Fig. 7) is journaled in the bearing 51 and carries upon its end the pinion gear 52. The latter pinion gear 52 meshes with a large gear 53 which is preferably made of fibre or similar material. The large fibre gear 53 is secured to the shaft 54 which carries upon its opposite end the small pinion gear 55. The latter gear 55 in turn meshes with another large gear 56 mounted upon and secured to the shaft 57. The shaft 57 likewise carries the small gears 58 and 59 which are shown to best advantage in Fig. 5. The small gear 58 serves to rotate the large sector arm gear 60. As shown in Fig. 12, the large gear 60 is secured to the revolving switch arm shaft 61 which is journaled in the bearing 62 at its innermost end and carries the metallic commutator sleeve 99 and the switch arm block 34 at its outermost end.

Referring back to Fig. 7, the second small gear 59 mounted upon the shaft 57 drives the gear 63 mounted upon the sleeve 64. The sleeve 64 is carried on the journal stud 65 which, in turn, is

secured to the journal plate 45 by means of the fastening nut 66. Adjacent the gear 63 and also secured to the sleeve 64 is the small gear 67 which meshes with the large motor switch gear 68. The latter gear 68 is of the same diameter as the 5 sector arm gear 60 and is concentrically mounted upon the shaft 61, but not secured thereto. It will thus be seen that by means of the gear train 59, 63 and 67, that the motor switch gear 68 is caused to rotate in an opposite direction and at 10 a lower speed than that of the gear 60. In the particular form of construction contemplated, the gear ratio of the train 59, 63 and 67 is so designed that the motor switch gear 68 will rotate at a speed which is one-fourth that of the 15 sector arm gear 60. As best shown in Figs. 7 and 13, the motor switch gear 68 has an integrally formed laterally projecting hub 69 and the diametrically oppositely disposed depressions 70 and 71 in the lateral gear face. The depressions 20 70 and 71 are adapted to receive the plunger 72 which is positioned in the sleeve 73 carried by the journal plate 45. The plunger 72 is adapted to actuate the motor switch contact arm 74. When the motor switch gear 68 is rotated in such a 25 position that the plunger 72 is clear of the depressions 70 and 71 and riding upon the face of the gear, the motor switch contact arm 74 will be forced against its associated contact arm 75. The contact arm 75 is positioned against the reinforcing arm 76 and mounted in the insulating switch block 77.

The laterally extending hub 69 of the motor switch gear 68 has a flattened portion 80. The plane of the flat portion 80 is parallel to that of 35 the diametric plane of the depressions 70 and 71. A contacting element 81 of insulating material is adapted to ride upon the face of the motor switch gear hub 69 and to actuate the contact arms 82 and 83 of the auxiliary motor switch 84. 40

The outer half of the revolving switch arm shaft 61 carries the solid ring 90 which is insulated from the shaft by means of the fibre sleeve 91. As shown in Fig. 6, the sector arm brush 92 is adapted to contact with the revolving ring 45 90. Referring to Fig. 12, the motor switch gear 68 is also adapted to mesh with the dismissal clutch gear 95 which is carried upon the shaft 96. The dismissal clutch mechanism is composed of the clutch driving plate 97 immovably 50 secured to the shaft 96. On the opposite face of the dismissal clutch gear 95 is positioned the friction plate 98, the degree of pressure which the friction plate 98 will exert upon the clutch gear 95 is regulated by means of the clutch arm 55 99 carrying the cams 100. The latter cams 100 are held in compression against the face of the friction plate 98 by means of the concentrically positioned helical springs 101 and 102. In order to prevent rotation of the dismissal shaft except 60 upon its proper actuation by means of the dismissal solenoid, which shall be later described, there is provided a metallic disc 103 eccentrically mounted upon the pin 106. The disc 103 carries the laterally extending and concentrically positioned pin 104 which is adapted to register with the recess 105 in the face of the dismissal clutch driving plate 97. As shown in Fig. 7 in order to automatically move the stop pin 104 out of registry of the recess 105 70 when the clutch is shifted into a different lateral position by means of the solenoid 42, there is provided the tension spring 107 secured to the periphery of the metallic disc 103 by means of the screw 108. The other end of the tension 75

spring 107 is secured to the face of the journal plate 44 by means of the screw 109.

The dismissal solenoid 42 which is adapted to shift the lateral position of the dismissal shaft 96 is essentially composed of the windings 110 and the adjustment means 111 and the solenoid plunger 112, the latter being coned at 113 to mate with the cup in the end of the stationary core 113' in order to prevent chattering when 10 alternating current is employed.

Mounted upon the outer end of the dismissal shaft 96 is the dismissal code wheel 114 secured thereto by means of the washers 116 and 117 and the fastening nut 118. The dismissal code wheel 114 has the major portion of its periphery composed of the smooth cam track 115. The remainder of its periphery is composed of the series of radially extending teeth 120 and the transverse recess 119. The dismissal code wheel follows 20 lower 121 mounted upon the arm 122 which is pivotally secured to the pin 123 is adapted to ride upon the peripheral surface of the code wheel 114. As the dismissal code wheel rotates, it will impart an oscillating action to the arm 122 which, in turn, functions to make and break contacts between the dismissal contact arms 124, 125 and 126. The stop strips 127 and 128 are secured adjacent the dismissal switch contact arms 125 and 126 respectively in order to limit 30 the travel of the contact arms 125 and 126. The latter contact arms are secured in lateral position by means of the terminal block 129. A fulcrum point 129a is positioned centrally of the base of the terminal block 129 so that by means of adjustment of the fastening screws, the relative angular position of the contact arms 125 and 126 may be regulated in relation to the oscillating arm 122.

When the dismissal code wheel is in inoperative position, the recess 119 is in registry with the follower 121, so that the arms 124 and 125 will be in contact. When the follower 121 rides out of the notch 119, the revolving switch arm circuit is broken with the result that the signal code 40 will not be transmitted. When the dismissal code wheel is rotated into such position that the follower 121 rides upon the teeth 120, the arm 124 will be forced into a series of contacts with the upper switch arm 126, transmitting the 50 dismissal code to the signal relay. When the follower 121 again registers with the recess 119, the revolving switch arm circuit is reestablished.

The construction of the supplemental switch is generally illustrated by Figs. 8 to 11 inclusive. Said switch is composed of the contact disc 130 rotatably mounted in the front plate 131. The insulating blocks 132 and 133 are secured in position to the rear of the plate 131 by means of the fastening screws 134. The contact disc 130 has the laterally projecting shaft 135 upon which is mounted the switch handle 136 which is removably secured thereto by means of the set screw 137. On the inner face of the switch handle 136 there is positioned the filister head screw 138 which is adapted to bear against the stop screws 139 and 140 in the face of the plate 131. By means of said screws 138, 139 and 140 it is possible to limit the degree of rotation of the switch handle 136 and its associated contact disc 139. As best shown in Fig. 10, the arcuate contacting strip 141 is mounted in the contacting face of the disc 130. The contacting strip 141 has the depressions 142 and 143 which are adapted to register with the contact pins 146 to 149 70 inclusive. Said contact pins are spring loaded

against the face of the contacting strip 141 by means of the compression springs 145. A plurality of ball bearings 144 are mounted in the inner face of the plate 131 in order to minimize the rotational friction of the disc 130. The contact pin 146 always remains in contact with the arcuate plate 141. As the disc 130 is rotated the contact pins 147, 148 and 149 come successively into contact with the plate 141 and are thereby electrically connected to the pin 146.

The wiring diagram (as illustrated in Fig. 14) representative of the various electrical circuits embodied in the apparatus will now be described.

Motor circuit

The motor circuit is as follows: wire 150, terminal T1, wire 151, terminal T7, wire 152, motor bars MB1 and MB3, motor bars MB2 and MB4, wire 153, terminal T8, wire 154, motor 40, wire 155, terminal T10, wire 156, terminal T3, wire 157, terminal T2, wire 158. It will thus be seen that the closing of the motor circuit and initial energization thereof is caused by making contacts between the motor bars MB1 and MB2 or the motor bars MB3 and MB4.

Motor switch circuit

The circuit connections for the regular limited call device which is dependent upon the actuation of the motor switch 77 by means of the motor switch gear 68 is as follows: wire 150, terminal T1, wire 151, terminal T7, wire 159, wire 160, contact arm 74, contact arm 75, wire 160', wire 161, terminal T8, wire 154, motor 40, wire 155, terminal T10, wire 156, terminal T3, wire 157, terminal T2, wire 158. It will thus be seen that actuation of the contact arms 74 and 75 serve to furnish energization of the motor 40 as long as said contacts 74 and 75 remain together.

Variable limited call circuit

The circuit connections of the variable limited call device as embodied in the functioning of the auxiliary motor switch 84 is as follows: wire 159, terminal T1, wire 151, terminal T7, wire 164, contact arm 83, contact arm 82, wire 162, wire 161, terminal T8, wire 154, motor 40, wire 155, terminal T10, wire 156, terminal T3, wire 157, terminal T2, wire 158. When it is desirous to render the auxiliary motor switch inoperative, its power-connecting wire 164 may be connected to the dead terminal T9 as shown by the position of the wire 163. However, when the auxiliary switch 84 is rendered operative by means of the connection of the wire 164, it will be seen that the main motor switch 77 is shunted and energization of the motor is continued until both switches 77 and 84 open.

Signal relay circuit

Wire 150, terminal T1, wire 151, terminal T7, wire 152, motor bars MB1 and MB3, selective switchboard bars, wires 165 to 191 inclusive, contact pins 20 to 26 inclusive, revolving switch arm 31, switch arm brush 92, terminal block 129, wire 167, contact arm 125, contact arm 124, wire 168, terminal T11, wire 169, terminal T4, wire 170, signal relay, wire 165, terminal T3, wire 157, terminal T2, wire 158. It will thus be seen that by selecting a variety of predetermined circuit connections by means of the insertion of the operating key 16 into the plug sockets 6 of the selective switchboard 19, that the various wires 185 to 191 inclusive will be placed in closed or open circuits so that upon contact of the revolving switch arm 31 with the contact pins 20 to 26 inclusive, a variety of electrical 70 75

impulses will be transmitted to the signal relay. The precise construction of the selective switchboard 10 has not been illustrated or described in the present specification inasmuch as it forms the subject matter of the United States patent to George Thompson, No. 1,230,946, issued June 26, 1917, and various improvements of which are set forth in my prior U. S. Letters Patent No. 1,823,221 granted Sept. 15, 1931. For the purposes of present convenience, however, in Fig. 14 there is represented the manner in which a regular code signal of single impulse is selected and transmitted. The vertical arrow drawn through the diagrammatic representation of the selective switchboard bars represents the position of the operating key 16. It will be noted that the bars 2-1, 3-1, 4-1, 5-1, 6-1, and 7-1 have suitably positioned notches in their edges so that the operating key will not contact with them. The sole contact will be made with the switchboard and bar 1-1 in such a manner that the electrical current from the motor bars MB3 and MB4 will be supplied only to the bar 1-1, to the wire 185, contact pin 26, and thence to the signal relay as has been already set forth and described.

Dismissal solenoid

The energization of the dismissal solenoid 42 and the consequent lateral shifting of the dismissal clutch shaft 96 is accomplished through the closing of the following electrical circuit. Wire 150, terminal T1, wire 171, terminal T5, wire 172, dismissal switch, wire 173, terminal T6, wire 174, terminal T12, wire 175, solenoid 42, wire 176, terminal T10, wire 156, terminal T3, wire 157, terminal T2, wire 158.

Dismissal code circuit

The wiring circuit for transmission of the dismissal code by means of rotation of the dismissal code wheel is as follows: wire 150, terminal T1, wire 151, terminal T7, wire 159, wire 177, contact arm 126, contact arm 124, wire 168, terminal T11, wire 169, terminal T4, wire 170, signal relay, wire 165, terminal T3, wire 157, terminal T2, wire 158. It will thus be seen that the alternate making and breaking of the contacts 124 and 126 will serve to impart the dismissal code impulses over the signal relay cable.

Supplemental switch circuit

The electrical connections which render operative the supplemental switch 7 are as follows: wire 150, terminal T1, wire 151, terminal T7, wire 178, contact pin 146, contact plate 141, contact pins 147, 148 or 149, wires 179, 181, or 182, contact pins 27 to 30 inclusive, revolving switch arm 31, switch arm brush 92, terminal block 129, wire 167, contact arm 125, contact arm 124, wire 168, terminal T11, wire 169, terminal T4, wire 170, signal relay, wire 165, terminal T3, wire 157, terminal T2, wire 158. Wire 180 connects both the supplemental contact pins 27 and 28 so that the shortest supplemental code signal that it is possible to select and transmit consists of two impulses. It is obvious that a supplemental code signal consisting of merely one impulse would be of no avail since the distinctive feature of the supplemental call signal is dependent upon the differential impulse interval. It will thus be seen that by selection of various contacts of the contact pins 147 to 149 inclusive that a variety of supplemental calls ranging from signals having two to four impulses in the particular instance, may be selected. When switch 7 is turned to the

position designated by the letter N (signifying normal), no supplemental code is set up and only the regular code will be transmitted.

Pilot lamp circuit

The wiring circuit for the pilot lamp 11 which is designed to inform the operator of the various calls which are being transmitted is as follows: wire 150, terminal T1, wire 151, terminal T7, wire 152, motor bars MB1 and MB3, selective switchboard bars, wires 185 to 191 inclusive, contact pins 20 to 26 inclusive, revolving switch arm 31, switch arm brush 92, terminal block 129, wire 167, contact arm 125, contact arm 124, wire 168, terminal T11, wire 184, pilot lamp 11, wire 183, terminal T10, wire 156, terminal T3, wire 157, terminal T2, wire 158.

Connected in parallel with the regular call contacts as above described, is the supplemental call circuit which also serves to energize the pilot lamp circuit.

Watchman's circuit

The circuit connections for the watchman's circuit which is an optional feature of the apparatus, is as follows: wire 150, wire 201, watchman's switch, wire 202, wire 170, signal relay, wire 165, terminal T3, wire 157, terminal T2, wire 158. The result of the closing of the latter circuit will be to transmit an impulse to the signal relay system so that the bells or lights will be energized throughout the plant. The above described watchman's circuit may be used to call the building attendant by pressing the button at the entrance.

The operation of the apparatus embodying the principle of my invention is substantially as follows. When the operating key 16 is inserted in any one of the plug sockets 6 of the selective switchboard 10, and rotated into such a radial position that contact is made between the motor bars, the motor 48 will then become initially energized to cause rotation of the revolving switch arm 31 and subsequent contact with the sector pins 20 to 26 inclusive. If the operating key 16 immediately after initial energization of the motor circuit is then rotated back into such a radial position that contact is no longer made between the motor bars due to the flat projection 19 on the end of the key, the operating mechanism will nevertheless continue to be energized due to the fact that the motor switch gear 68 has actuated the plunger 72 to bring together the motor switch contacts 74 and 75. The energization of the gear train and revolving switch arm will continue through two cycles of revolution until the plunger 72 again registers with one of the depressions 70 or 71 in the face of the motor switch gear 68, at which time the arms 74 and 75 will spring back out of contact and interrupt further operation of the mechanism. On the other hand, if it is desirous to continue the cycle of operations through four repetitions, the wire 164 leading from the auxiliary motor switch 84 is connected to the power terminal T7 so that the main motor switch 77 will be shunted. In this manner the auxiliary motor switch contact arms 82 and 83 will not be opened until the motor switch gear 68 has completed an entire revolution and its flattened hub portion 80 returns to registry with the insulated follower 81.

When the dismissal signal switch is closed, the solenoid 42 will be actuated, the code wheel 114 put in motion by the switching mechanism (elements 97 to 101 inclusive), the revolving switch 75

arm circuit opened by the separation of the arms 124 and 125, and the dismissal code signal will then be transmitted, interrupting and superseding the regular and supplemental code signals.

5 When the supplemental call switch 7 is so positioned that two or more of the contact pins 27 to 30 are energized, then the supplemental call signal will also be transmitted subsequently to that of the regular code signal. By means of the 10 expedient of changing the relative position of the revolving switch arm 31 on its shaft 61 into the position 31' as shown in Fig. 2, it is possible to transmit the supplemental call prior to the regular code call. As has been previously indicated, 15 in order to maintain a uniform interval between the transmission of the supplemental and the regular codes when the former is transmitted prior to the latter, it is necessary to reverse the coding order of the regular code and of the supplemental code, so that the last impulse of the supplemental code shall occur at the contact pin 30 and the first impulse of the regular code will begin on the contact pin 20. By way of example, 20 supposing that it is desired to transmit a signal consisting of a regular code denoting the number 22 and a supplemental code consisting of three impulses, the contacts 22, 23, 25 and 26 will be connected into the circuit by means of the selective switch plug 16 and the supplemental code 25 contacts 27, 28 and 29 will be connected in the circuit. Thus when the revolving switch arm turns in a counter-clockwise direction, the interval between the last of the regular code, namely, the contact with the terminal 26, and the first 30 impulse of the supplemental code, the contact with terminal 27, will be spaced apart at an interval corresponding to the time interval between the terminals 26 and 27. When the transmission of the signal order is reversed, in order to 35 transmit the same code signal, the electrical connections will likewise be reversed so that the terminals 24, 23, 21 and 20 will be connected and the terminals 30, 29 and 28 of the supplemental code will be connected, whereby a uniform interval 40 corresponding to the distance between terminals 20 and 30 will separate the transmission between the two codes. The latter expedient has not been illustrated in the accompanying drawings due to the fact that the reversal of electrical 45 circuits is a device well understood by those skilled in the art.

It should also be observed that the selective switchboard connections are so arranged that

the last impulse of the regular code call will always occur on the last contact pin 26, when the regular code is transmitted prior to the supplemental code.

Other modes of applying the principle of my 5 invention may be employed instead of the one explained, change being made as regards the mechanism herein disclosed, provided the means stated by any of the following claims or the equivalent of such stated means be employed. 10

I therefore particularly point out and distinctly claim as my invention:

1. In a driving mechanism for a selective signalling apparatus, the combination of a motor for the prime movement of said mechanism, a 15 motor switch and an auxiliary switch connectible in parallel electric connection therewith, and actuating means for said switches comprising a rotating gear and a hub laterally extending from said gear, the latter having a plurality of concentrically positioned depressions in its face adapted to register with a plunger for actuating said motor switch, and said hub having a flattened portion to register with means for actuating said auxiliary switch, said depressions being 20 adapted to actuate said motor switch at intervals corresponding to the time for the transmission of a certain number of such signals, and said flattened portion being adapted to actuate said auxiliary switch at intervals corresponding to 25 30 a greater number of repetitions of such signals.

2. In a driving mechanism for a selective signalling apparatus, the combination of a motor for the prime movement of said mechanism, a motor switch and an auxiliary switch connectible 35 in parallel electric connection therewith, and actuating means for said switches comprising a rotating gear and a hub laterally extending from said gear, the latter having a plurality of concentrically positioned depressions in its face 40 adapted to register with a plunger for actuating said motor switch, and said hub having a flattened portion positioned in synchronization with one of said gear face depressions to register with means for actuating said auxiliary switch, said 45 depressions being adapted to actuate said motor switch at intervals corresponding to the time for the transmission of a certain number of such signals, and said flattened portion being adapted to actuate said auxiliary switch at intervals corresponding to 50 50 a greater number of repetitions of such signals.
